Primary Examiner — Mitchell I. Siegel*(74) Attorney, Agent, or Firm* — Plumsea Law Group, LLC(57) **CLAIM**

The ornamental design for a lacrosse head, as shown and described.

DESCRIPTION

FIG. 1 is a top isometric perspective view of a lacrosse head showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

The evenly-spaced broken lines illustrate portions of the lacrosse head that form no part of the claimed design. The dot-dash lines are included as boundary lines and form no part of the claimed design.

1 Claim, 7 Drawing Sheets(56)
